(51) **LOC (14) Cl.** **14-04**
(52) **U.S. Cl.**

CLAIM

USPC **D14/485**

The ornamental design for a display screen or portion thereof with a graphical user interface, as shown and described.

DESCRIPTION

(58) **Field of Classification Search**

USPC ..... D14/485—95

U.S. PATENT DOCUMENTS

4,838,384 A 6/1989 Thangavelu
5,506,898 A 4/1996 Costantini et al.
5,742,845 A 4/1998 Wagner

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof with a graphical user interface.

The outer broken lines showing the display screen or portion thereof forms no part of the claimed design. The remaining broken lines showing portions of the graphical user interface form no part of the claimed design.
